(57) **CLAIM**

The ornamental design for a monitor bracket, as shown and described.

DESCRIPTION

FIG. 1 is an exploded perspective view of the monitor bracket, including a bracket and a flange.

FIG. 2 is a perspective view of the assembled monitor bracket, including the bracket and the flange.

FIG. 3 is a front view of the assembled monitor bracket, the back view being a mirror image thereof.

FIG. 4 is a top view of the monitor bracket.

FIG. 5 is a bottom view of the monitor bracket.

FIG. 6 is a right side view of the monitor bracket, the left side view being a mirror image thereof.

FIG. 7 is a front view of the monitor bracket, the back view being a mirror image thereof.

FIG. 8 is a top view of the flange of the monitor bracket.

FIG. 9 is a bottom view of the flange of the monitor bracket.

FIG. 10 is a right side view of the flange of the monitor bracket.

FIG. 11 is a left view of the flange of the monitor bracket; and,

FIG. 12 is a front view of the flange of the monitor bracket, the back view being a mirror image thereof.

The features shown in broken lines in the Figures form no part of the claimed design.
